ELWOOD GRISSINGER, OF BUFFALO, NEW YORK, ASSIGNOR TO LUCY ASH GRISSINGER,
OF BUFFALO, NEW YORK.

PHONOGRAPH AND ANALOGOUS APPARATUS.

1,339,648.

Specification of Letters Patent. Patented May 11, 1920.

Application filed June 12, 1918. Serial No. 239,513.

To all whom it may concern:

Be it known that I, ELWOOD GRISSINGER, a citizen of the United States, and resident of Buffalo, in the county of Erie and State 5 of New York, have invented certain new and useful Improvements in Phonograph and Analogous Apparatus, of which the following is a specification.

My present invention is shown as embodied in a phonographic sound box which is primarily adapted for mechanically reproducing sound from a record but it may be embodied in a phonographic recorder or other apparatus where rigid, frictionless, 15 noiseless pivoting is necessary or desirable in order to insure faithful, undistorted mechanical receiving or transmission of high frequency or complex wave energy.

In my prior application, Serial No. 20 236,735, filed May 27th, 1918, I have disclosed a construction wherein the effects of mechanical resonance are eliminated from the vibratory system, by making the lever arm rigid and pivoting it upon spaced piano 25 steel wires stretched to the safe limit of their tensile strength thereby insuring a predetermined, rigidly fixed path of movement for all parts or particles of the lever.

My present invention relates more particularly to the use of the spaced stretched wires and it involves in addition thereto, a means for further predetermining and fixing the location of the pivotal axis of the lever. Broadly stated, the said means consists of a third element adapted to apply a thrust perpendicularly to the plane of the wires, and along a line parallel with and midway between them. The means employed for this purpose may be varied, but 40 in this application I disclose how a pair of alined steel balls may be used for such purpose.

By providing suitable adjusting screws, the pivotal means may be very powerfully 45 forced against the lever thus affording a convenient and very effective means for transversely displacing the wires and thereby stretching them to any desired degree of tension.

50 By the above expedient, the alined balls become the physical bearing surfaces for the pivotal movement of the lever. These bearing surfaces are forced into contact with relatively enormous pressure by the 55 symmetrically applied stresses of the spaced

wires. This prevents all possibility of jumping or noise producing movements at the point of contact of the lever with its bearing. The bearing parts are preferably of very hard steel and are formed with 60 smooth, preferably polished surfaces.

My invention will be more fully understood from the following detailed description thereof in connection with the accompanying drawings, in which—

65 Figure 1 is a face view of a phonographic sound box showing the spaced stretched wire suspension;

Fig. 2 is a section on the line 2—2, Fig. 1, the lever and pivotal mounting being 70 shown in side elevation;

Fig. 3 is an enlarged vertical section on the line 3—3, Fig. 1;

Fig. 4, is an elevation endwise of the lever;

75 Fig. 5 is a detail view showing the pivotal mounting as in Fig. 4 but on a larger scale; and Fig. 6 is a detail section showing a modified form of adjustable ball support.

In these drawings, the sound box 80 comprises the annular ring 1, formed with the inwardly projecting annular flange 2, and the back-plate 3, secured to ring 1 by screws 4. In the recess between flange 2 and plate 3 is clamped the diaphragm 5 of mica or 85 other suitable material, disposed between a pair of rubber cushioning rings 6 which may be of any known or desired material or construction.

The annular ring 2 is formed on one side 90 with an enlargement 7 adapted to form a solid base support for the mounting of the stylus lever. The backplate 3, is shown as provided with an annular rubber collar 8 carrying an internal ring 9 provided with 95 lugs 10 adapting it for bayonet connection with slots on a phonograph arm where the device is used for reproducing or a mouth-piece where the device is used for recording.

100 The lever arm 11 may be attached to the diaphragm directly or through the screw and adjustable nuts shown in Fig. 2. The other end of the lever is provided with a socket 12 and binding screw 13 for holding a needle for reproducing or a cutting point 105 for recording, as indicated at 14. This lever is preferably of an aluminum alloy, and the long arm thereof may be made light yet very rigid. The pivotal portion is relatively massive for purposes of strength, and be- 110

cause a certain amount of weight near the pivotal axis is not so objectionable and is in some respects advantageous so far as concerns pure tone transmission.

- 5 The resilient members adapted to permit resilient pivotal movements of the lever while powerfully opposing movements in other directions are shown as comprising 2 wires 15, 16, symmetrically arranged with
- 10 respect to the pivotal axis and also with respect to the longitudinal axis of the lever. The wires are secured to the lever arm in any desired way, as for instance, by threading them through passages 17, 18 (Fig. 3).
- 15 These passages are preferably parallel with each other and with the diaphragm.

The ends of the wires are secured to steel clamping posts 19, 20 by steel clamping plates 21, 22, each secured preferably by a central bolt 23, passing downward between the wires so that the clamping plates will bind equally on both of the wires to be secured thereby.

As shown in the drawings, the wires are 25 comparatively close together where they pass through the lever and are spread apart to a considerably wider distance at their clamping points so that when highly tensioned, they have considerable effect in bracing or 30 staying the lever against longitudinal movement and also against any skewing of its pivotal axis.

Such spaced wires when very highly tensioned afford a frictionless, noiseless mounting for pivotal movement of the lever about an axis parallel with and midway between the wires. According to my present invention, I use a physical means for determining the axis consisting of a pair of alined balls 35 24, 24, applied against the lower side of the lever so as to have two alined points of contact therewith in a plane midway between the spaced wires. The balls 24 are preferably the very hard, polished steel balls such 40 as are commonly used for ball bearings. They may be thrust upward vertically 45 against the lever as powerfully as may be desired, by means of screws 26, 26.

The stress of the wires against the balls 50 being in a direction endwise of the screws, it is, of course, possible to use a single screw for each ball, and the ball may be located in a conical recess in the end of the screw as indicated in Fig. 6. For some reasons, 55 however, it is preferable to use a special adjustable mounting for the balls and a special bearing surface for the lever. As shown in Figs. 3, 4 and 5, the balls are supported on a bed plate 27, which may be of hardened 60 steel if desired, formed with V grooves 28 parallel with each other and parallel with the plane of movement of the lever arm. The plate 27 is slidably mounted on a centering stud 29, and four screws, 26, are 65 shown for supporting the plate and for ad-

justably applying the desired upward thrust against the lever arm.

The lever surface against which the balls bear, may be a separate steel plate 30, secured to the lever arm by screws 31. The bearing surface on the plate 30 may be provided with a transverse groove 32. This groove may be of circular cross-section of considerably greater radius of curvature than the balls. Being at right angles to the 75 grooves 28 in the bed plate 27, they together afford a convenient means for locating and centering the balls so that they will be in a line exactly transverse to the lever, will be spaced a fixed distance apart, and their line 80 of thrust will be midway between the planes of downward stress of the spaced wires 26.

The position of the wires 26 may be accurately fixed with reference to the transverse groove 32 by forming clamping 85 grooves therefor in the plate 30 and coöperating grooves in the bottom surface of the lever. The latter surface may be a separate plate 33. Plate 30 preferably is and plate 33 may be of hardened steel, especially 90 where the lever is made of aluminum or aluminum alloy for purposes of lightness. This is because under ordinary conditions of use, the vibration of the lever will cause the 95 highly tensioned piano wires to rapidly cut aluminum, aluminum alloys or even ordinary soft steel.

Where ordinary bearing balls are used, the surfaces bearing on the lever will of course be spherical and while this theoretically gives a slight rocking contact instead of a mathematically exact pivotal movement about a single axis, nevertheless, for the very slight movements involved in phonographic work, any rolling component in 100 the movement will be very small. Even if the proportions of the parts are such as to give considerable rocking movement, this movement will nevertheless be rigidly and precisely predetermined, so that the paths 105 of movement of all points or particles of the lever arm will be invariable even though not absolutely perfect arcs of circles perfectly concentric with a single axis. If the balls are no larger than $\frac{1}{8}$ of an inch in diameter 110 the departure from the true circle movement will be small, and if the balls be only half as large, that is $\frac{1}{16}$ of an inch diameter, the departure will be only one-quarter as great and will be negligible. 115

The balls may be set with the bearing surfaces thereof at the desired height with reference to the clamping points of the wires by means of the set screws or they may be permanently fixed in such position, with the 125 wires strung loosely through the lever and clamps. Then the wires may be stretched to the desired tension by any suitable tensioning appliances, after which the clamps may be screwed tight. The maximum ten- 130

sioning with least displacement of the wires and least danger of breaking them, may be obtained by the same method except that the bearing will first be retracted, and after 5 stringing, highly tensioning and clamping the wires in a single plane, the bearing is screwed up to deflect the wires and thereby increase the tension to the desired extent. The adjustable bearing may be used as the 10 sole tensioning appliance, the wires being drawn snug by hand in a single plane so as to get them practically equal and symmetrical, then clamped and bearing screwed up until the desired tension is applied.

15 The spacing as well as the divergence of the wires may be varied, as for instance, they may be clamped close together and diverge to more widely separated points for passage through the lever, as set forth in 20 my said prior application, and they may be otherwise varied within wide limits, provided only, that they be spaced apart so as to afford spaced apart planes of opposition to the thrust of the ball bearings which 25 should take effect in a plane between them in order to produce the desired condition of stable resilient stresses.

Dust, dirt and rust producing moisture may be excluded, and the smoothness of the 30 bearing surfaces preserved by employing a thin layer of soft felt 34, surrounding the balls and through which the balls project, as indicated in Fig. 3. I find that in practice, this may be conveniently accomplished 35 by assembling the parts with an unperforated pad between the balls and the lever, the great pressure exerted by subsequent tightening of the wires being sufficient to crush the fibers of the felt out from between 40 the bearing surfaces. When thus arranged, the felt fibers extend into intimate relation with the bearing points and afford an efficient and convenient means for conveying thereto lubricating oil which I preferably 45 employ as an agent for perfecting the smoothness and noiselessness of the pivotal movement.

From one viewpoint, the preferred embodiment of my present invention may be 50 considered as involving the use of the highly tensioned wires of my said prior application, Serial No. 236,735, in combination with a solid physical means for determining the pivotal axis and as a substitute for the noisy, 55 imperfectly acting springs, etc., which have been employed heretofore in phonographic apparatus, in the vain attempt to prevent jumping, rubbing and shifting of the pivotal bearing surfaces of the lever. The 60 wires employed by me when stretched to sufficiently high tension, eliminate all noises due to the imperfect or rubbing contact of the bearing surfaces and they introduce no noises of their own because the free portions 65 thereof are of such small mass and of such

high tension that any natural frequency vibrations which may be set up in them are of very small total energy and are of too high frequency and too musical in quality to be observable among the wave forms 70 transmitted therethrough either in recording or reproducing.

Furthermore, my physical bearing and stretched wire combination is remarkably effective in eliminating "needle noises" 75 which are so often disagreeably prominent in reproduction of sounds from ordinary records. There is some reason to believe that the relatively massive proportions of the part of the lever arm utilized for sus- 80 taining the thrust of the bearing and the stress of the stretched wires, in combination with extreme lightness of the remainder of the lever arm contribute to some extent to the decrease and practical elimination of 85 needle noises.

The instrument being substantially free from needle, bearing, spring and other disturbing noises, damping, which is commonly employed for the purpose of reducing such 90 noises, is unnecessary. The damping in my device is extremely small, and is limited mainly to internal molecular friction which operates substantially equally for all frequencies. This avoids the unequal damping 95 out of the higher frequencies and the resulting distortion which is inevitable where the damping is due to friction.

Regardless, however, of explanations as to causes, it is a fact that a phonograph reproducer made in accordance with my present disclosure, faithfully produces, without 100 needle noises and without any internally originated noises or notes, all of the more delicate overtones traced in the record not 105 observably reproduced by any phonograph apparatus now on the market and it does this in louder volume and without the "needle noises" and without adding any internally generated noises or notes of its 110 own. This superiority holds even when the tension of the wires is decreased very far below the safe limit of tensile strength of the wire.

For the resilient tension members, I prefer to use wire approximately like "No. 6 piano wire" which is fine quality steel wire about .011 to .012 inch in diameter, but the material and size of the wire may be varied within wide limits and I have at different 115 times and with various objects in view used finer wires and also larger wires up to .02 and even 0.34 inch in diameter. It is obvious also that tension members other than wire may be employed and that the cross 120 section need not be circular.

I claim:

1. In an apparatus of the class described, a lever, means for pivotally vibrating said lever, a suitable support, and means for piv- 130

totally mounting said lever on said support, said means comprising pivotal bearings, one of which is formed with curved contact surfaces in combination with steel wires of 5 great tensile strength secured to the support and engaging said lever symmetrically with respect to the pivot and extending in directions adapted to stress said lever against said surfaces, and adjustable means 10 for stretching said wires to a tension approaching the limits of safe elastic stress.

2. In an apparatus of the class described, a lever, means for pivotally vibrating said lever, a suitable support and pivotal bearings, one of which is a steel ball bearing, in combination with highly tensioned wires secured to the support, engaging said lever adjacent said ball bearing and extending in directions adapted to stress said lever 15 against said ball bearing and to afford balanced stresses adapted to prevent lateral skewing of the lever upon said bearing, and adjustable means for forcing said bearing against said lever to vary the tension of the 20 wires or the position of the pivotal axis.

3. In an apparatus of the class described, a lever, means for pivotally vibrating said lever, a suitable support and bearings, one of which comprises alined steel balls having 30 pivotal contact with the lever on a line at right angles to the plane of its pivotal movement, in combination with highly tensioned wires secured to the support and engaging said lever symmetrically with respect to the 35 pivotal line and extending in directions adapted to stress the pivotal bearing surfaces into continuous non-slip engagement.

4. In an apparatus of the class described, a lever, means for pivotally vibrating said 40 lever, a suitable support and bearings, one of which comprises a pair of alined steel balls having pivotal contact with the lever on a line at right angles to the plane of its pivotal movement, in combination with 45 highly tensioned wires secured to the support, engaging said lever adjacent said line of pivotal contact and extending in directions adapted to stress the pivotal bearing surfaces into continuous non-slip engagement and to afford balanced stresses in other 50 directions adapted to prevent skewing of the lever upon said balls.

5. In an apparatus of the class described, a lever, means for pivotally vibrating said 55 lever, a suitable support, a solid bearing having pivotal contact with the lever at spaced apart points on a line at right angles to the plane of its pivotal movement, in combination with highly tensioned wires secured to 60 said support and engaging said lever symmetrically with respect to the line of pivotal contact and extending in directions adapted to stress said lever against said bearing.

6. In an apparatus of the class described, 65 a lever, means for pivotally vibrating said

lever, a suitable support, a solid bearing having pivotal contact with the lever on a line at right angles to its plane of movement, in combination with highly tensioned wires secured to said support and engaging said lever adjacent said line of pivotal contact and extending in directions adapted to stress said lever against said bearing and to afford balanced lateral stresses adapted to prevent skewing of the lever upon the bearing. 70

7. A sound box having a diaphragm, a lever secured to the diaphragm, bearings on the box and on the lever contacting with each other on a line parallel with the diaphragm, in combination with wires secured 75 to the sound box and engaging the lever from different directions such as will afford tension stresses coöperating to press the lever bearing downward upon the box bearing, but mutually opposed and approximately balanced in other directions, and adjustable means for moving said box bearing and lever substantially against the downward pressure to increase the tension of the wires substantially equally. 80

8. A sound box having a diaphragm, a lever secured to the diaphragm, bearings on the box and on the lever contacting with each other on a line parallel with the diaphragm, in combination with resilient tension members secured to the sound box and engaging the lever from different directions such as will afford tension stresses coöperating 85 to press the lever bearing downward upon the box bearing, but mutually opposed and approximately balanced in other directions, and adjustable means for moving said box bearing and lever substantially against the downward pressure to increase the tension of the resilient tension members substantially 90 equally. 95

9. A sound box having a diaphragm, a lever secured to the diaphragm, bearings on the box and on the lever having contact on a line parallel with the diaphragm, in combination with a plurality of steel wire rigidly clamped to the sound box and engaging the lever, arranged to afford mutually opposing tension stresses having a resultant pressure transversely of the lever and means operating 110 to force the lever substantially in the direction of said pressure, thereby varying the tensions of mutually opposing wires substantially 115 equally. 115

10. A sound box, a diaphgram, a radially extending lever secured to the diaphragm and pivotally mounted on the box, the pivotal means including spaced clamps mounted on the sound box in symmetrical relation, on opposite sides of the lever, steel wires 120 stretched between the clamps and the lever and engaging the lever at symmetrically spaced points on opposite sides of the lever and on opposite sides of its pivotal axis, the free portions of the wires between the clamps 125 130

and the lever being arranged diagonally to stay said lever against lateral and endwise movement, in combination with means for stretching the wires to increase their tension 5 substantially equally.

11. A sound box, a diaphragm, a radially extending lever secured to the diaphragm and pivotally mounted on the box, the pivotal means including spaced clamps mounted on the sound box in symmetrical relation, on opposite sides of the lever, steel wires stretched between the clamps and the lever and engaging the lever at symmetrically spaced points on opposite sides of the lever 10 and on opposite sides of its pivotal axis, the free portions of the wires between the clamps and the lever being arranged diagonally to stay said lever against lateral and endwise movement, in combination with 15 means for applying a transverse thrust upon the lever in a direction perpendicular to the plane of engagement of said wires with the lever and in a plane passing between them.

12. A sound box, a diaphragm, a radially extending lever secured to the diaphragm and pivotally mounted on the box, the pivotal means including spaced clamps mounted on the sound box in symmetrical relation, on opposite sides of the lever, steel wires stretched between the clamps and the lever and engaging the lever at symmetrically spaced points on opposite sides of the lever and on opposite sides of its pivotal 30 axis, the free portions of the wires between the clamps and the lever being arranged diagonally to stay said lever against lateral and endwise movement, in combination with a bearing adapted to contact with the lever 35 on a line parallel with its pivotal axis and to apply a thrust at right angles to the plane of the spaced points of engagement of the wires with the lever and passing midway between said points.

13. In an apparatus of the class described, a lever, means for pivotally vibrating said lever, a suitable support, a pair of aligned balls mounted on said support and having pivotal contact with the lever on a line at 40 right angles to the plane of its movement, and resilient devices for forcing said lever downward upon said balls, and means for spacing the balls consisting of V-shaped 45 depressions formed in the surface which supports them.

14. In an apparatus of the class described, a lever, means for pivotally vibrating said lever, a suitable support, a pair of aligned balls mounted on said support and having 50 pivotal contact with the lever on a line at right angles to the plane of its movement, and resilient devices for forcing said lever downward upon said balls, and means for spacing the balls and permitting pivotal 55 rolling thereof, said means consisting of 60

V-shaped grooves formed in the ball support parallel with the lever and at right angles to its pivotal axis.

15. In an apparatus of the class described, a lever, means for pivotally vibrating said lever, a suitable support, a pair of aligned balls mounted on said support and having pivotal contact with the lever on a line at right angles to the plane of its movement, and resilient devices for forcing said lever 70 downward upon said balls, the bearing surface of said lever being formed as a groove extending transversely of the lever, formed on straight line elements at right angles to the lever and curved lengthwise of the lever 75 whereby pressure of the resilient devices tends automatically to set the lever at right angles to the balls.

16. In an apparatus of the class described, a lever, means for pivotally vibrating said lever, a suitable support, a pair of aligned balls mounted on said support and having pivotal contact with the lever on a line at right angles to the plane of its movement, and resilient devices for forcing said lever 80 downward upon said balls, the bearing surface of said lever being formed as a groove extending transversely of the lever, formed on a straight line, elements at right angles to the lever and curved lengthwise of the lever 85 whereby pressure of the resilient devices tends automatically to set the lever at right angles to the balls, and means for spacing the balls and permitting pivotal rolling 90 thereof, said means consisting of V-shaped 95 grooves formed in the ball support parallel with the lever and at right angles to its pivotal axis.

17. In an apparatus of the class described, a lever, means for pivotally vibrating said lever, a suitable support, a pair of aligned balls mounted on said support and having pivotal contact with the lever on a line at right angles to the plane of its movement, and resilient devices for forcing said lever 100 downward upon said balls, and means for lubricating the bearing surfaces, said means consisting of a felt pad inclosing the balls between the lever and ball support.

18. In an apparatus of the class described, a lever, means for pivotally vibrating said lever, a suitable support, a pair of aligned balls mounted on said support and having pivotal contact with the lever on a line at right angles to the plane of its movement, and resilient devices for forcing said lever 110 downward upon said balls, and means for lubricating the bearing surfaces, said means consisting of a felt pad pinched between the balls and the lever.

Signed at Buffalo in the county of Erie and State of New York this 10th day of June, A. D. 1918.
